Des. 203,865
Patented Feb. 22, 1966

203,865

OUTDOOR LIGHT FIXTURE

George D. Cooper, 1136 Vista Place, Edmonds, Wash.

Filed May 28, 1965, Ser. No. 85,501

Term of patent 14 years

(Cl. D48—20)

FIG. 1

FIG. 2

FIG. 3

FIG. 4

FIG. 5

FIG. 1 is a front elevational view of the outdoor light fixture embodying the new design;

FIG. 2 is a side elevational view of the outdoor light fixture shown in FIG. 1;

FIG. 3 is a rear elevational view of the outdoor light fixture shown in FIG. 1;

FIG. 4 is a top plan view of the outdoor light fixture shown in FIG. 1; and

FIG. 5 is a bottom plan view of the outdoor light fixture shown in FIG. 1.

I claim:

The ornamental design for an outdoor light fixture, as shown and described.
